UNITED STATES PATENT OFFICE.

AMOS CALLESON, OF BROOKLYN, NEW YORK.

BOTTLE FILLING AND SEALING MACHINE.

Application filed December 14, 1921. Serial No. 522,207.

To all whom it may concern:

Be it known that I, AMOS CALLESON, a citizen of the United States, residing at Brooklyn, in the county of Kings and State 5 of New York, have invented certain new and useful Improvements in Bottle Filling and Sealing Machines, of which the following is a specification.

This invention relates to machines for filling and sealing bottles or similar containers, and it consists in certain improvements whereby the filling and sealing of bottles one after another may be made to take place very rapidly and with the least 10 amount of loss of pressure, as in filling with charged liquids, and whereby the construction of the various parts is rendered simple and efficient and the work of the attendant serving the machine is reduced to simply 15 watching the operations. It will simplify understanding of the improved machine to preface the present description thereof with the remark that the various operations occur 20 while the bottles are moved in a procession 25 at a constant level and that the forming of a sealed space around each bottle head at the time of filling and before sealing the effecting of a certain interlock between parts concerned in the sealing or closure-affixing 30 operation, and the introduction of the closure into position over the bottle head preliminary to the affixing or sealing are accomplished by resort to fluid pressure, the second and third of these operations being 35 in the present adaptation actually accomplished by utilizing the pressure of the air which in filling is discharged from the bottle.

In the drawings,

40 Figure 1 is a side elevation of the machine, partly in vertical front to rear section;

Figure 2 is a horizontal sectional view on the line 2—2, Fig. 1;

45 Figure 3 is a plan, partly in section, of the cylinder *k* forming a part of the rotary upright of the machine, the stationary cam housed in said cylinder and one of the fitting mechanisms;

Figure 4 is a front elevation of one of the 50 filling mechanisms;

Figure 5 is a side elevation of the main and compensating slides and Figure 6 is a vertical sectional view of the same;

Figure 7 shows the main slide, the compensating slide and parts of the fluid conducting and controlling means in front elevation, partly in section;

Figure 8 is a sectional detail illustrating principally how syrup is supplied to the 60 syrup-gaging cup;

Figure 9 is a sectional view on the line 9—9, Fig. 11;

Figure 10 is a sectional view on the line 10—10 of Fig. 7;

Figure 11 is a horizontal sectional view of the compensating slide and gate taken just above the plug 36 in Fig. 6;

Figure 12 is a sectional view on the line 12—12 of Fig. 7;

Figure 13 is a side view of the main cam *o*;

Figure 14 is a plan of said cam;

Figures 15, 16 and 17 are sectional views on the lines 15—15, 16—16 and 17—17 of 75 Fig. 13; and

Figure 18 is a vertical sectional view of a modification of what is shown in Fig. 6, Figs. 19 to 21 being details thereof.

On the base *a* is arranged an arched 80 pedestal *b* for the hopper *c* for the closures. The back part of the base is depressed and affords a step-bearing *d* and also a socket *e* for a fixed upright shaft *f* around which revolves on the step-bearing an upright including the following parts: a cylindrical 85 basal member *g* to which is affixed a turret *h*; a nut *i* journaled in and concentrically with member *g*; and a superstructure comprising three members rigidly secured together and forming practically a unit, to wit, the threaded sleeve *j* having its threading engaged with nut *i*, the cylinder *k* surrounding the sleeve, and the head *l* surrounding said cylinder, said superstructure 90 being adapted to be adjusted vertically in the basal member by turning the nut which at *m* is geared with a suitable manually 95

- turnable spindle *n* journaled in the basal member. Parts *j*, *k* and *l* form a casing for a barrel cam *o* which does not rotate but which may move up or down with said superstructure on adjusting the latter, the same being splined at *p* to the (non-rotary) shaft *f*. The turret has affixed thereon or forming a part thereof an upstanding ring *q* which is recessed peripherally at regular intervals to receive the bottles, which stand upon the turret. *h** and *k** are telescoped portions of *h* and *k*, splined together as shown so as to insure member *k* rotating with the rest of the upright.
- 15 The top of the base forms a table *r* over which the bottles slide in passing to and from the turret, it being flush with the top of the turret and cut away (Fig. 2) to receive the same. Above the table are arranged two minor turrets *h'*, *h''*, each peripherally recessed to receive the bottles, one functioning to deliver bottles to and the other from the main turret *h*. All three turrets are geared together, as indicated at 20 *s s* in Fig. 2, and they are rotated (i. e., the aforesaid upright, including turret *h* turning bodily) at constant speed in any desired way, as by the worm-and-worm-wheel connection *t* between a suitably driven drive shaft *u* and the depending shaft *v* of one of the minor turrets. The direction of rotation is shown by arrows, Fig. 2; suitable guides *w* may be provided to direct each empty bottle into a recess of turret *h'* and 25 retain it there until said turret has deposited the bottle on turret *h* and in a recess thereof, and to shunt each filled bottle off turret *h*, retain it in a recess of turret *h''* for a time and then cause its discharge from the machine. The recesses in the several turrets are spaced so as to synchronize and form bottle sockets as those of the main and either minor turret come into registry with each other.
- 30 35 A disk-like table *x* is fixed on head *l* and its periphery is received in a recess *y* formed in the hopper *c* so that, though the table rotates, it supports the hopper, which has a depending stem *c'* guided in the pedestal *b*; said recess may be equipped with anti-friction bearings above and below the periphery of the table, and one of these, as the lower one *z*, may if desired form part of the means for agitating the closures in the hopper and insuring their proper delivery to the hopper chute 2, these details being not fully shown because they constitute no part of the present invention. Table *x* carries a syrup tank 3 provided with a standpipe 4 by which at 5, subject to the control of a ball-float 6, syrup is supplied to the tank, the standpipe (which rotates with and penetrates table *x*) being capped by the stationary delivery fitting 7 of a pipe 8 leading from a suitable source of syrup supply.

Contained in the upper part of the standpipe is a pipe 9 which forms therewith, between them, the syrup passage and whose bore forms with the bore at the lower part of the standpipe a passage for the carbonated water, this pipe (which rotates with the standpipe and projects above it) having on its upper end the stationary delivery fitting 10 of a pipe 11 leading from a suitable supply of carbonated water. The fittings and pipes 4 and 9 are suitably packed.

There is provision for nine bottles on the turret *h* at a time. As they are carried around thereby each undergoes filling and sealing. There are nine vertically movable mechanisms which perform these operations, one arranged above each bottle position. They are all alike, and the description of one will therefore serve for all.

In each of nine vertical guideways 12 (Fig. 3) formed in cylinder *k* of the aforesaid rotary upright is movable a main slide 13 which has a roller 14 projecting through an opening 15 (Fig. 1) in said cylinder and engaged in the camway 14' of the stationary cam *o*. In the vertical bore 16 of the slide is vertically movable the tubular stem 17 of the sealing head 18 into the upper end of which is screwed the plug portion of a head-piece 19, the parts 17, 18, 19 forming what I term the compensating slide; the slide has a toothed hardened face 20 and the inner end of a block 21, movable horizontally toward and from said slide and in the head-piece, has a correspondingly toothed hardened face 22, the purpose of which will appear later. The compensating slide has an interior flange 23 against which abuts upwardly an annular closure-applying device 24 of any approved form, the same being supported by an annulus 25 which affords at 25' a closure-supporting ledge and is in turn supported by the rubber gasket 26 which is held against said annulus under a certain amount of pressure, but so as to leave an annular space or chamber 27 therearound, by the mouth-piece 28 screwed onto the sealing head. A plunger 29, formed with a cylinder 30 in its upper end and with a downward protuberance 31 which penetrates flange 23, is normally held pressed against a rubber gasket 32 on said flange by a strong spiral spring 33 interposed between said plunger and the plug of the head-piece 19. Against the lower end of its portion 31 the closure, superimposed on the bottle head, is adapted to bear. Said plunger 29 has a vertical bore 34 which has held therein, by a nut 35 (Fig. 9), an exteriorly spirally ribbed plug 36 penetrated longitudinally by a port or vent 37. Parallel with this bore it also has a port 38 adapted to connect the space of cylinder 30 with the space of the sealing head below the flange 23. In cylinder 30 is the head 39 of a piston whose stem 130

40 is guided for vertical movement in the head-piece 19 and penetrates block 21, having an inward incline or cam-face 41 adapted, when the piston is raised, to shift the block inwardly to cause its teeth to engage in those 20 of the slide 13. The lower face of the piston head 39 is adapted to abut the top of plug 36 but it has one or more groove-like ports 42 (Fig. 9) whose function will 0 appear. The piston will be depressed when the slide 13 rises by a depresser 43 depending from table x. 44 is a vent from the interior of the plunger above flange 23 to the atmosphere.

5 The closure-entrance 45 to the filling-head is formed to deliver a closure, supplied there to from the chute 2 as it passes the same, onto the closure-supporting ledge 25'; but the closure is at first prevented from moving 10 onto the ledge by a pair of convergently arranged stop-pins 46 whose inner ends it abuts, their outer ends forming pistons in cylinders 47 formed in the sealing-head and having vents 48 to the atmosphere and containing 25 light springs 49 which tend to urge the pins inwardly. Around the entrance 45 is formed a channel containing a continuous rubber gasket 50, the face of the sealing-head in which said chamber is formed and 30 the exposed face of the gasket being beveled as shown in Fig. 6. The channel forms behind the gasket a chamber 51 which communicates with chamber 27 by a port 52. When a closure is admitted to the entrance 35 the entrance is to be closed and at a certain point in the operation thereafter the closure is to be pushed positively to its seat on the closure-supporting ledge. For this purpose a gate member 53, U-shaped in plan (Fig. 40 11), is fulcrumed on a pin 54 at the back of the sealing-head, which it straddles; the gate member normally tends to assume the position shown in Fig. 1, but when the sealing-head descends a roller 55 on a depending 45 arm of the gate engages a cam 56 on the part k* and causes the gate to assume the horizontal position shown by Fig. 5 so that the inner face of its body or outer portion, which is beveled to correspond to the bevel 50 on the sealing-head and gasket 50 (see dotted line 57, Fig. 5), will be face to face with the gasket. Said body portion forms a chamber 58 with an outlet 59 to register with the closure-entrance 45 and with which 55 communicates a cylinder 60 containing a piston 61 which is pivotally connected to a bent lever or pusher 62 whose free end is adapted to be thrust, on movement of the piston, into or out of the closure-entrance. 60 The piston is moved to cause the inward movement of the pusher by fluid-pressure; opposite movement thereof is caused by a lever 63 which hangs pivotally pendant from the slide 13 and, by its inclined surface 63' 65 wiping against a cam 64 (Fig. 1) in the de-

scent of the slide, is moved against a protruding part of said piston (Figs. 5, 9 and 11).

The slide has suitably secured to its side faces the valve chambers 65 and 66 having vertical passages 65' and 66' and valve seat 65'' and 66'' therein. These valve chambers deliver liquid to the interior of the filling head the former to afford pressure for the performance of certain functions and the latter for the filling of the bottles. Telescoped into the passages of these valve-chambers are the upper ends of pipes 67 and 68 which deliver into the filling head respectively below and above its flange 23, the joint in each case being sealed by a gland 69; a port 67' leads from pipe 67 to the chamber 27 (see Fig. 9). Valves 70 71 are adapted to seat at 65'' 66'', respectively, their stems protruding upwardly through glands 72 and having heads 70' 71' under which take the arms of a two armed lever 73 fulcrumed in slide 13 (Figs. 1, 3, 4, 5 and 7). The bore of valve chamber 65 is longitudinally channeled, as at 65''' down to the valve-seat to permit fluid flow past the valve when it is unseated. Lever 73 has upstanding arms 73' each formed with a shoulder 73'' which abuts a stud 74 on the head-piece 19 when the sealing-head is fully depressed in the slide; upward movement of the sealing-head in the slide will, by studs 74 wiping past said shoulders, cam back lever 73, raising the valves 70 71 from their seats. In valve-chamber 65 is a horizontally arranged port 75 (Figs. 7 and 12) which is connected by a port 76 to the bore of said chamber and which contains a valve 77 normally spring-held against a seat 75' to close said port; 100 with this port is connected the lower member of a telescoped pipe 78 the upper member of which depends from the table x. In valve-chamber 66 are arranged two other horizontally arranged ports 79 80 which are 105 connected by an inclined port 81 (compare Figs. 3, 7 and 10) with the bore of said chamber and which respectively contain valves 82 83 spring-held against seats 79' 80' to close said ports; with these ports 79 80 110 are respectively connected the lower members of telescoped pipes 84 85 which depend from a syrup-gaging cup 95 to be described, (only 85 communicating, however, with the cup). The stems of all the valves 77 82 83 115 protrude rearwardly and are suitably packed to prevent leakage. Arranged to be respectively opposite them when said stems have moved down with slide 13 and movable in cylinder k are the poppets 86 87 88 which 120 wipe against camways 86' 87' 88' on cam o. The bore of valve chamber 65 may be put into communication with the atmosphere (to release the pressure above valve 70 for a purpose to appear) through a port 89 125 adapted to be closed by a valve 90 which is 130

moved to closing position by the poppet 86, through the intermediary of a plunger 91 and a spring 92, when said poppet is moved to open valve 77 (Figs. 3, 7 and 12).

5 Water to enter the valve-chambers 65 66 is conveyed from the pipe 9—4 through a pipe 93 having a T 94 connected with the two telescoped pipes 78 84.

The syrup in the tank 3 is adapted to flow

10 to a gaging cup 95 through a pipe 96 when a normally spring-closed valve 97 is opened through the medium of a lever 98 fulcrumed on the rotating upright and having a roller projecting through an opening 99 (Fig. 4)

15 in said upright and bearing on a camway 91' of cam o. According to the height to which a tube 100 slideable vertically in the top of the cup and open at top and bottom is adjusted the cup is adapted to receive a cer-

20 tain quantity, more or less, of syrup, (valve 97 of course remaining open at least until the syrup thus attains its level in the cup). The cup discharges into telescoped pipe 85, as already stated.

25 *Operation.*—The position of the mechanism for the filling and capping of each bottle at the start of the cycle of that operation is shown by Fig. 1, slide 13 being then held by the cam o fully elevated. As it

30 passes the chute 2 a closure is by any suitable means (not concerned with the present in-vention) allowed to enter the closure en-

35 trance 45 of the filling-head and rest against pins 46 (Fig. 9), the gate being depressed as shown in Fig. 1. At o' (Fig. 13) cam-

40 groove 14' depresses slide 13 and causes plunger 29 to impinge against the bottle head, the filling-head 18 being telescoped over the same, the result of which is the

45 checking of the descent of the compensating slide sufficiently to cause pins 74 to rock lever 73 even for the shortest bottle and thus effect both compensating for varying heights of bottles and, by the movement of said

50 lever, the opening of the valves 70 71. If, as in the filling and consequent increase of pressure within the bottle (as will appear), the bottle should collapse, the compensating slide will fall, allowing the valves to close

55 as soon as the pins 74 clear the shoulders of lever 73. In the position thus assumed by the slide 13 the valves 77 82 83 come into opposition to their poppets 86 87 88 (see Fig. 4). As the main slide 13 descends the

60 gate 53 is closed by its roller wiping over cam 56.

The rotation continuing poppet 86 is actuated by camway 86' to open valve 77, and water under pressure from the T 94 (that is, it may be and in fact in the present case is charged water from the same source from which the water for filling comes) flows by

65 pipe 67 and port 67' to annular chamber 27 and thence through port 52 to chamber 51 and causes gasket 26 to form a seal around

the bottle neck and gasket 50 to press against the gate and form a seal around the closure-entrance 45; gasket 32 is already compressed between plunger 29 and flange 23 so that now the interior of the filling-head is sealed off 70 from the atmosphere, except for a certain controlled vent 101 (Figs. 7 and 11) which is to be referred to. The cam 86' holds the valve 77 open for a great part of the cycle (see Fig. 16), so as to maintain the sealed 75 condition of the filling head until, the bottle having been filled, the closure is pressed against the bottle head in the final act of sealing or closing.

Continued rotation brings poppet 88 into 80 position to be actuated by camway 88' and this opens valve 83, permitting the (as will be seen) measured charge of syrup in cup 95 to flow by gravity via 68 into the bottle; it passes down the spirally ribbed exterior of 85 the plug 36 and the air which it (and the charged water, which is to follow) displaces from the bottle passes up through port 37, enters cylinder space 30 via 42, flows down through port 38 to the main space of the 90 filling-head and thence through opening 59 of the gate into its chamber 58, where it acts ultimately to cause piston 61 to exert pressure on the finger 62 which, when the cap is freed, will force it into position over the 95 bottle head.

Further rotation clears poppet 88 from camway 88', so that valve 83 cuts off the syrup pipe 85, and brings poppet 87 to position to be actuated by camway 87' and so 100 open valve 82, so that the charged water from T 94 follows the syrup through 68 and down exteriorly of the spirally ribbed plug 36 into the bottle, the air displaced from the bottle continuing to flow into the filling-head and gate-chamber 58. The air pressure thus stored in the filling head and gate-chamber not only actuates the finger 62, as stated, but it raises the piston 39 and so causes its stem to move block 21 so that the 110 compensating slide is now locked to the main slide as a preliminary to the closure-applying operation. If, on the collapse of a bottle, the compensating slide tends to fall so as to close the valves 70 71, block 21 will 115 offer no resistance because the air-pressure that has been stored up as just explained will then be released, allowing piston 39 to fall by gravity and the block to recede. The air stored as aforesaid I find is more than 120 enough for performing the functions mentioned; wherefore I provide at a suitable point, as at 101, Figs. 5 and 11, a vent controlled by a needle-valve which may be adjusted to allow that leakage which will 125 avoid bottle-breakage without unduly reducing the pressure.

Continued rotation will, at the rise o'' in 130 camway o, result in a slight upward and downward movement of slide 13, plunger

29 separating from the bottle head, which is held down by the pressure in the filling-head, and the closure, being now above the latter and free to move onto ledge 25', is 5 pushed to a position between the bottle head and plunger by finger 62; the pins are forced back by the closure assisted by the pressure in the filling-head, the air in their cylinders 47 venting at 48. In the return or down- 10 ward movement of the slide the plunger presses the closure against the bottle head, and since the slide now assumes its lowest level (see o''' in Fig. 13) the sealing device 24 is moved down relatively to the plunger 15 and so affixes the closure to the bottle. This results in breaking the seal at gasket 32, so that the pressure stored in the filling-head is vented at 44. As the slide assumes its lowest level lever 63 engages cam 64 and 20 so acts to draw finger 62 out of the closure-entrance 45, so that the gate can fall.

Immediately thereafter poppet 86 runs off camway 86' and not only allows valve 77 to re-seat to cut off the liquid pressure that has 25 been holding gasket 26 constricting the bottle neck and gasket 50 pressed against the gate but valve 90 (Fig. 12) to vent valve-chamber 65 above valve 70, so that the pressure in chambers 27 and 51 falls and said 30 gaskets retract, releasing the bottle and the gate.

Finally the slide assumes the original level (rising thereto at incline o''' , Fig. 13), and after the amount of the movement allowed 35 for compensating has been taken up and valves 70-71 are incidentally re-seated the compensating slide rises with it clear of the bottle, the depression of the piston 39-40 being assured by the depresser 43. As the 40 slide rises the gate falls by gravity to the position shown in Fig. 1.

As soon as valve 83 is closed by poppet 88 running off the camway 88' the camway 91' causes lever 98 to open valve 97 so that the 45 cup is refilled from the tank 3, camway 91' being shown of a sufficient extent to allow the cup to be filled to the extreme height to which tube 100 may be adjusted.

Part h on the one hand and slide 13 with 50 slide 17 constitute opposed pressure members between which the bottle or other container is held in such manner that if the bottle should collapse for any reason the slide 17, constituting a container-opposed 55 portion of one of the members yieldable from but normally urged toward the other member, will effectuate the closing of the normally closed valves 70-71, which it opens on yielding.

60 The release of pressure from the fluid passage of the filling or sealing head via port 44, caused by the bottle elevating the plunger 29, is done in the present example as a sequent of the filling of the bottle and 65 the closing thereof—i. e., the pressure be-

ing no longer required because the bottle has been closed it is released (and released, it may be noted, at a definite point and in a controlled way). The lower part of port 38 is in fact a groove, so that when the 70 plunger rises the pressure is relieved from chamber 30 down port 38 and then laterally under and past gasket 32 to port 44, and from the interior of head 18 below flange 23 upwardly via the groove part of port 38 and then laterally under and past gasket 32 to said port 44.

As has been pointed out, the valves 70, 71 prevent fluid flow (even though the valves 77, 83 and 82 are opened on each 80 cycle) so long as a bottle is absent. Of course the principal object is to avoid spilling the liquids on or about the machine, although in the machine in question it also prevents pressure being admitted to chamber 27 unless a bottle head is present in the gasket to resist such pressure and thereby prevent the gasket from being blown out of its seat. In the construction shown in 90 Figs. 18 to 21 the contraction of the gasket is effected by fluid pressure the same as before, but such pressure does not depend on presence or absence of a bottle but is admitted on every cycle in any event—which is a matter of omitting the valve 70, while 95 leaving valve 77 to be opened on every cycle as already described, and constructing the mechanism so that there will be means to prevent the blowing out of the gasket by the pressure whenever it is admitted with 100 no bottle present. In Figs. 18 to 21 the parts 13, 14, 16, 17, 18 (17 and 18 being here separately formed but suitably united as one rigid structure), 19, 20, 21, 22, 23, 24, 25 (being here integral with 18) 25', 105 26, 27 and 28, are all substantially the same as before. The closure inlet 45, the gasket 50, the chamber 51 behind the same, port 52 connecting said chamber and chamber 27, and port 67' by which fluid enters chamber 27 from pipe 67 are all also substantially the same as before. The plunger, 110 here designated 102, formed at its upper end with a cylinder 103, has its downward protuberance 104 extended so that when the plunger is fully depressed its lower end obturates and nearly fits the hole in gasket 26 and so, on admission of fluid to chamber 27 with no bottle present, prevents collapse 115 or blowing out of the gasket; the plunger has the vertical bore (105) and therein the spirally ribbed plug (106) held therein by the nut (107) and provided with the port or vent (108), and it also has parallel with 120 its bore the port (109) connecting the space of cylinder 103 with the space of the sealing head below flange 23. The plunger is contained as to its cylindrical part in a sleeve 110 whose flange 110' limits downward movement of the plunger to the ex-

125 130

tent stated and shown, the sleeve being held against vertical movement between a packing ring 111 resting on flange 23 and a spacer sleeve 112 interposed between the sleeve and head-piece 19. The spring 113, corresponding to spring 33, here rests on a disk 114 resting on the sleeve 110. The piston, having its head 39 in cylinder 103 and its stem 40 guided in head-piece 19 and 10 provided with a cam-face 41, coacts with block 21 and is in all respects substantially the same as before, excepting that the area of the piston head is less than that of the protuberance of the plunger. The syrup and filling liquid enter the plunger 102 from pipe 68 through a projecting nipple 102' thereon (Fig. 21), stem 17, sleeve 110 and slide 13 having suitable slots 17', 110" and 13' (Figs. 19 and 20) to accommodate said 15 nipple. The operation of the machine modified as in Figs. 18 to 21 is as follows: When the filling head receives a closure on passing the shute 2 said closure comes to rest against the protuberance 104 of plunger 102, which then stands depressed. The main slide then descends, bringing the plunger against the head of the bottle, the plunger being thus held from further descent while the compensating slide continues down and until the plunger abuts disk 114, whereupon the descent of the compensating slide also is stopped to effect compensation and actuate the lever 73 for the opening of the valve 71 in the way already 20 clearly explained. The meeting surfaces of the bottle head and plunger are now about coincident with the top plane of closure inlet 45, so that now the bottle prevents inward movement of the closure contained in the inlet. The mechanism now comes around to the positions where valves 77, 83 and 82 are opened in the way already explained so as, respectively, to admit pressure to chambers 27 and 51 to constrict gasket 26 around 25 the bottle neck and press gasket 50 against the (now elevated) gate 53 and thus enclose the bottle mouth in a sealed space and then admit first the syrup and then the filling liquid, the air driven from the bottle passing up through the bore of plug 106 and then down to said space through port 109 so to provide the pressure necessary to actuate pusher 62 upon the closure being free to move inward and also acting in chamber 103 30 to raise piston 39—40, which thus acts, as already explained, to lock the compensating and main slides together. Valves 83 and 82 having closed, the mechanism undergoes the slight rise at o" (Fig. 18) to effect separation of plunger 102 from the bottle (which will remain seated or held down by the pressure on its support as the plunger is also held up because the area in the now restricted gasket is greater than the area of 35 piston head 39), upon which the pusher

forces the closure to its seat 25' over the bottle head. When, following said rise, the main slide moves to its lowest limit, the plunger comes against the closure on the bottle head, and its downward movement being thereby stopped the appliance 24 is telescoped down over the closure and thus affixes it to the bottle head, spring 113 being put under tension so that when the ensuing rise of the main slide occurs the capped bottle will be ejected from said appliance. The plunger and piston are returned to their lowest limits by depresser 43 when the main slide approaches its highest position the same as already explained. The venting of the pressure stored up in the sealing head of course takes place downward through gasket 26 as soon as, valve 77 having been closed, valve 90 is allowed to open to relieve the pressure in chamber 27, so that gasket 26 (and also gasket 50) retracts in the way already explained. 40

Having thus fully described my invention, what I claim as new and desire to secure by Letters Patent is:

1. In combination, opposed means to exert affixing pressure on a container and closure interposed between them, one being movable toward and from the other to exert such pressure and one including a container-opposed portion and having said portion yieldable therein and one having means during the pressure stroke first to pass a fluid under seal into the container and then affix the closure thereto, and means, controlled by the pressure of the fluid while passing under seal into the container, to lock said container-opposed portion in non-yielding relation to that one of said means having said portion. 45

2. In combination, opposed means to exert affixing pressure on a container and closure interposed between them, one being movable toward and from the other to exert such pressure and including a container-opposed portion and having said portion yieldable therein and also means during the pressure stroke to pass a fluid under seal into the container and then affix the closure thereto, and means controlled by the pressure of the fluid while passing under seal into the container, to lock said container-opposed portion in non-yielding relation to said one of the opposed means. 50

3. In combination, opposed means to exert affixing pressure on a container and closure interposed between them, one being movable toward and from the other to exert such pressure and including a container-opposed portion and having said portion yieldable therein and also means during the pressure stroke to pass a fluid under seal into the container and then affix the closure thereto, and means, contained in said portion and controlled by the pressure of the 55

fluid while passing under seal into the container, to lock said container-opposed portion in non-yielding relation to said one of the opposed means.

- 5 4. In combination, with a supporting structure and a container-support, an up-and-down movable main slide over the support, an upwardly yieldable normally depressed compensating slide in the main slide 10 having means during the downward stroke of the main slide to pass a fluid under seal into the container and then affix a closure thereto, means to interlock the compensating slide with the main slide against yielding therein, and means, controlled by the pressure of the fluid while passing under seal into the container, to control said interlocking means.

5. In combination, with a filling and closure-affixing head adapted to pass a fluid under pressure into a container with an appliance for applying the closures, the head having an opening to receive the container mouth portion in opposition to but spaced 25 from said appliance, means to support a closure temporarily out of interposed relation to said appliance and container mouth portion, and also means to seal off the interior of said head from the atmosphere upon said 30 mouth portion and closure being received therein, means, actuated by the fluid in the head, to move the closure into interposed relation to said mouth portion and appliance.

6. In combination, with a filling and closure-affixing head adapted to pass a fluid under pressure into a container and with an appliance for applying the closures, the head having an opening to receive the container mouth portion in opposition to but spaced 40 from said appliance, means to support a closure temporarily out of interposed relation to said appliance and container mouth portion, and also means to seal off the interior of said head 45 from the atmosphere upon said mouth portion and closure being received therein, means, including a cylinder communicating with the interior of the head and a piston in the cylinder, to move the closure into interposed relation to said mouth portion and 50 appliance.

7. In combination, a filling head member for filling containers with fluid under pressure having an opening thereto and adapted 55 to be united and form a sealed space with the interior of the container to be filled, a cover member for the opening movable into and out of face to face relation to the exterior of the first member, a gasket arranged 60 between said members and movable in one of them against the other member, and means to introduce fluid from the interior of the head member and behind the gasket to press the same against said other member.

- 65 8. In combination, a hollow filling head

adapted to pass liquid into and having a contractile gasket to receive a container and a fluid chamber around the gasket, means to introduce fluid to said chamber to contract the gasket, and a plunger normally 70 projecting into the gasket and opposing contraction thereof, said plunger being displaceable out of the gasket by the container on telescoping of the latter into the gasket.

9. In combination, a hollow filling-head 75 member having therein an affixing appliance and also having an opening opposite to but spaced from said appliance to receive a container member adapted to enter said appliance, a plunger protruding from said 80 appliance toward said opening and movable from the latter by the container member, said filling-head member having means to admit a closure laterally against the plunger, means to press the closure against the plunger, 85 means to cause movements of one of said members relatively to the other first to enter the container member into said filling-head member and against the plunger to move the latter clear of the closure, then to 90 separate the container member and plunger while retaining the latter in the filling-head member and then to enter the container member into said appliance, means to seal off the interior of the filling-head member 95 from the atmosphere during the second of said movements, and means to admit fluid pressure to the filling head also during the second of said movements.

10. In combination, with a filling and closure-affixing head adapted to pass a fluid under pressure into a container and with an affixing appliance within said head, the head having an opening to receive the container mouth portion in opposition to but spaced 105 from said appliance, means to support a closure temporarily out of interposed relation to said appliance and container mouth portion, and also means to seal off the interior of said head from the atmosphere 110 upon said mouth portion and closure being received therein, a closure check normally held in position to obstruct movement of the closure into interposed relation to said appliance and container mouth portion but 115 adapted to be moved by the pressure within the head clear of the closure.

11. In combination, opposed means to exert affixing pressure on a container and closure interposed between them, one being 120 movable toward and from the other to exert such pressure and one including a container-opposed portion and having said portion yieldable therein and one having means during the pressure stroke first to pass a fluid under seal into the container and then affix the closure thereto, means controlled by the pressure of the fluid while passing under seal into the container, to lock said container-opposed portion in non-yielding relation to that one 125 130

of said means having said portion, a normally closed valve for said means to pass fluid, and means, activated by said container-opposed portion on yielding thereof, to open said valve.

12. In combination, a frame, a closure-affixing means, a carrying structure for said means journaled on a vertical axis in the frame and having its upper part vertically 10 adjustable, and a closure receptacle guided

for up and down movement in the frame and arranged laterally of but overhanging said upper part of said structure, said part having a surface on which the overhanging portion of the receptacle is supported and has wiping contact, and said receptacle having means to deliver closures to the closure-affixing means.

In testimony whereof I affix my signature.
AMOS CALLESON.
